UNITED STATES PATENT OFFICE.

TOM DRAKE AND ERIC GAYTER, OF ALTRINCHAM, ENGLAND, ASSIGNOR TO LINOTYPE AND MACHINERY LIMITED, OF LONDON, ENGLAND, A COMPANY OF GREAT BRITAIN.

ESCAPEMENT MECHANISM OF TYPOGRAPHICAL COMPOSING MACHINES.

Application filed February 2, 1922. Serial No. 533,606.

To all whom it may concern:

Be it known that we, TOM DRAKE and ERIC GAYTER, both subjects of the King of the United Kingdom of Great Britain and 5 Ireland, and residing at Linotype and Machinery Works, Altrincham, in the county of Chester, England, have invented new and useful Improvements in the Escapement Mechanism of Typographical Composing 10 Machines, of which the following is a specification.

This invention relates to the escapement mechanism of typographical composing machines such as those known commercially 15 under the trade mark "Linotype", and particularly mechanism which includes escapement levers formed in one with their respective pallets. When levers of this kind are mounted in the machine so as to rock 20 each about a single pivot, their pallets enter and leave the magazine channels by arcual movement of short radius, which has been found to be less satisfactory than the movement of the pallets of the more expensive 25 construction in which such pallets are themselves pivoted to the rocking escapement lever. Consequently, it has been sought to secure the advantages accruing 30 from the movement of the pallets of the last named construction, from escapement levers each formed as a single entity with its pallets, by mounting each escapement lever so 35 that it is caused to move arcually instead of pivotally. The object of the present invention is to provide improved means for securing 40 such arcual movement of each escapement lever as a whole about an axis outside of its own marginal edges, whereby the radius of arcual movement of the pallets is increased as compared with that secured 45 by the above-named pivoting.

The invention will now be described by reference to the accompanying drawings which represent in vertical section corresponding parts of the same magazine and differing only in respect of the escapement lever, which latter is represented, in Figure 1, in normal position and in Figure 2 as 50 when operated for releasing the lowermost matrix contained in the corresponding magazine channel.

According to the constructional form of the present invention represented in the

drawings, the escapement lever 1 is formed with a curved or arcual slot 2 traversed by 55 two stationary parallel wires or rods 3 which are common to all the escapement levers of the same bank. The positions of the wires 3 and the curvature of the slot 2 are such that the pallets 4, 5 integral with 60 the escapement lever 1, move as nearly as practicable perpendicularly to the general plane of the magazine 6 to which the said escapement levers 1 are fitted.

The escapement levers 1 may be rocked 65 by any of the well-known means; the devices illustrated comprise the ordinary plungers 7 which, when moved upward by the pivoted strikers 8, (only parts of which are shown) press against the heels 9 of the levers 1 and 70 rock or move them across upon the wires 3 antagonistically to springs 10 which bear upon the rear ends or tails 11 of the said levers and thereby release a matrix 12, all 75 in the usual manner, excepting as regards the transverse movement of the escapement levers transverse of the wires 3.

In the example illustrated, the slot 2 is an arcual one struck from a centre 13 which constitutes the before-mentioned axis about 80 which the escapement lever 1 is caused to rock, but it is to be understood that the said slot may be otherwise than arcual, and moreover that supports other than the two wires 3 may be provided; for instance, the 85 bearing constituted by these wires may be provided by a single rod of arcual cross section or having guiding surfaces at only its longitudinal edges.

Having described our invention, we declare that what we claim and desire to secure by Letters Patent is:—

1. In or for an escapement mechanism of a typographical machine, the combination of an escapement lever formed with an inferior curvilinear slot, and a bearing traversing said slot and engaging the walls thereof at a plurality of points in the length of the lever, whereby the lever is caused to rock about an axis located outside of its 95 own marginal edges.

2. In or for an escapement mechanism of a typographical machine, the combination of an escapement lever, and a bearing on which the lever is mounted to slide in a curvilinear 100 path, the said lever being slotted to provide

interior guiding surfaces engaged with the bearing at a plurality of points in the length of the lever.

3. In or for an escapement mechanism of a typographical machine, the combination with an escapement lever having its matrix-engaging pallets integral therewith and having an interior arcual slot, of stationary par-

allel rods traversing said slot whereby the lever is guided to rock about an axis located 10 outside of its own marginal edges.

In testimony whereof we have affixed our signatures hereto.

TOM DRAKE,
ERIC GAYTER.
